UNITED STATES PATENT OFFICE.

RALPH A. WOODING, OF KENSINGTON, CONNECTICUT.

HAME-CHIME.

SPECIFICATION forming part of Letters Patent No. 349,623, dated September 21, 1886.

Application filed April 21, 1886. Serial No. 199,606. (No model.)

To all whom it may concern:

Be it known that I, RALPH A. WOODING, a citizen of the United States, and a resident of Kensington, in the county of Hartford and State of Connecticut, have invented certain new and useful Improvements in Hame-Chimes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of as much of the collar and hames of a harness as will illustrate the application of my improved hame-chime. Fig. 2 is a similar view of the chime removed from the hames and collar; and Fig. 3 is a vertical sectional view of one 20 of the bells and its standard.

Similar letters of reference indicate corresponding parts in all the figures.

My invention has relation to chimes of bells for applying to the hames and collar of a set 25 of harness; and it consists in the improved construction and combination of a chime having a yoke or frame, which may be secured upon the collar under the hames without any other means for fastening it than the hames, as 30 hereinafter more fully described and claimed.

In the accompanying drawings, the letter A indicates a yoke having a shape corresponding to the shape of the upper portion of the collar, and this yoke may be placed with its 35 legs resting in the groove B in the collar C, the hames D being thereupon placed over the legs of the yoke, retaining them in place.

The hame-strap E is placed into the concave upper side of a transverse curved bar, 40 F, at the top of the yoke, the said bar having its ends curved upward, and the upwardly-bent ends will prevent the yoke from slipping

to either side, the ends engaging the strap. A bow or frame, G, is secured with its ends to the legs of the yoke, being either cast integral with the yoke or being secured to the same, and the upper portion of the bow is provided with a number of posts or uprights, H, to the ends of which the bells I of the chime are secured. The posts are preferably formed, as shown in Fig. 3, with a shoulder or collar, J, near the upper end, and terminating with a screw, K, and the central perforation of the bell, and of the frame supporting the hammers or clappers L, fit upon this 55 screw and are secured by the nut M. The shoulder will afford a wide support for the under side of the perforated portion of the bell, and will thus keep it in its proper position and prevent it from being tilted to the 60 sides.

The yoke and frame may be either cast in one piece, or they may be made of malleable metal in separate pieces, and be united by means of rivets or similar means.

Having thus described my invention, I claim and desire to secure by Letters Patent of the 65 United States—

A hame-chime consisting of a yoke formed to conform to the shape of the upper portion of a collar and provided with a cross-bar at its upper end formed with upwardly-bent ends, and of a frame secured with its ends to the legs of the yoke, and having a chime of bells secured to uprights upon it, as and for the purpose 75 shown and set forth.

In testimony that I claim the foregoing as my own I have hereunto affixed my signature in presence of two witnesses.

RALPH A. WOODING.

Witnesses:

CHARLES M. BROWNE,
CORNELIA S. BROWNE.
